UNITED STATES PATENT OFFICE.

CHARLES OSBORNE, OF NORTH ATTLEBOROUGH, MASS., ASSIGNOR TO THE WHITING MANUFACTURING COMPANY.

DESIGN FOR FORK AND SPOON HANDLES.

Specification forming part of Design No. 7,902, dated November 24, 1874; application filed November 14, 1874.
[Term of Patent 7 years.]

To all whom it may concern:

Be it known that I, CHARLES OSBORNE, of North Attleborough, Bristol county, Massachusetts, have invented a Design for Handles for Forks and Spoons, of which the following is a specification:

I propose to distinguish it by the name Italian. The nature of the design is fully represented in the accompanying photographic illustrations, to which reference is made.

Figure 1 is a face view of a spoon with a handle according to my design. Fig. 2 is a view of the reverse side.

The distinctive features are found in the form of the decorative elevations and depressions.

On the face the finger-piece A of the handle is slightly convex, and sinks, with a rounded edge, to a flat margin, B. At the junction of the finger-piece with the stem is a beaded cross-band, D, growing narrower toward a small rosette, C, in the center, beyond which, on the stem E, the sunk border is continued, and the space between becomes a narrow bead. Near the junction of the spoon is another cross-band, G, with a rosette, F. Above the band D is a cluster of foliage, H, composed of diverging curved stems intermingled with lobate leaves. A narrower series of curved stems extends below or toward the spoon. On the

back face the finger-piece on the reverse of A is concave. A portion along the edge is raised in a narrow bead, B'. The bead is bent to follow the contour of the edge, past the bands D and G, dying away as it merges into the body of the spoon. On the reverse of the rosette C and adjacent ornaments is a small cluster of foliage, C'. A bead extends along the center of the stem and connects the ornament C' with a leaf at the junction of the stem with the spoon.

I claim as my design for spoon and fork handles—

1. The front face, having the convex finger-piece A, sunk border B, and foliate ornament H, as shown and described.

2. The front face, having the two bands D and G, the bead in the center of the stem, and foliate ornament H, as shown and described.

3. The back face, having a concave finger-piece with a bead along the edge, and the foliate ornament C' at the junction of the finger-piece with the stem, as shown and described.

In testimony whereof I have hereunto set my hand this 7th day of November, 1874, in the presence of two subscribing witnesses.

CHARLES OSBORNE.
